UNITED STATES PATENT OFFICE.

HARRY N. ATWOOD, OF LYNN, MASSACHUSETTS, ASSIGNOR TO GENERAL ELECTRIC COMPANY, A CORPORATION OF NEW YORK.

ELECTRIC METER.

981,236.

Specification of Letters Patent. Patented Jan. 10, 1911.

Application filed August 20, 1908. Serial No. 449,413.

To all whom it may concern:

Be it known that I, HARRY N. ATWOOD, a citizen of the United States, residing at Lynn, county of Essex, State of Massachusetts, have invented certain new and useful Improvements in Electric Meters, of which the following is a specification.

My invention relates to meters, and more particularly to so-called mercury meters where an armature revolves in a receptacle containing mercury, and has for its object certain improvements in the construction of such meters which will make them cheaper to construct and more reliable.

I accomplish the object of my invention by the use of a disk armature revolving in a flat receptacle containing mercury and being subject to the influence of two magnets diametrically opposed with respect to the armature in order to balance each other's effect upon the armature, and thus, as far as possible, eliminate friction; and also by the use of an indicating pointer which turns through nearly 360° , and thus gives the instrument a greater range and allows the position of the pointer to be read with greater ease than may be done in the usual forms of indicating meters.

Further improvements are pointed out more particularly in the appended claims.

For a further understanding of my invention, reference may be had to the accompanying drawings, where—

Figure 1 is a front view of my new meter, with a portion of the cover removed, and certain portions in section in order to show more clearly the construction of the meter; Fig. 2 is a side view partially in section; and Fig. 3 is a top view of the meter with the top portion removed, for a clearer understanding of my invention.

I have shown a back 1, to which is attached a cover 2 by any suitable means, the front of the cover being composed of a sheet 3 of glass, or some transparent material. Attached to the back of the meter I have shown a member 4, which supports the working parts of the meter and attached to the lower portion of the member 4 I have shown a member 5, which is substantially disk-like in shape. Beneath the member 5, and attached thereto, I have shown member 6 of substantially the same shape as member 5, but not in close contact with member 5, except at the edges; so that there is left be-

tween these two members a space 7, which may be filled with mercury or any suitable conducting liquid, and in which space surrounded by the liquid filling the space revolves armature 8, which is made in the shape of a disk, and of any suitable conducting material. The armature is connected to a shaft 9, which bears at its lower extremity against a bearing 10 let into member 6 in any well known manner, and at its upper extremity bears against bearing 11, which is supported by arm 12 of member 4.

I have shown two C-shaped magnets 13, which are made up of punchings of magnetic material; the magnets being supported by arms 14 of member 4 in such a way that they are diametrically opposed with reference to the armature of the meter. One pole of these magnets, 15, extends through the top of cover 5 of the meter, so as to be in close relation to the armature, and the other pole 15' fits closely against member 6, which I prefer to make of some magnetic material, such as cast iron, while member 5 may be made of some non-magnetic material, such as aluminum. Surrounding magnets 13, I have shown coils 16, which are potential coils, and are connected across the conductors of the circuit which I desire to measure, coils 16 being so wound that poles 15 of each magnet will be of opposite polarity. 17 are conductors which are brought into contact with the mercury of the meter on the diametrical line on which the magnets 13 are placed, and which are in close relationship with the armature 8, and extend through suitable bushings 17' to insulate them from members 5 and 6. Conductors 17 are connected by conductors 18 to studs 19, which extend through a suitable insulating member 20 through the back of the meter, and may be used for fastening the meter to any suitable support; and are also used for conveying the current from the circuit to be measured.

Attached to the armature shaft is a small weight 21, which partially counter-balances the buoyant effect of the mercury upon the armature, and may be slipped down, so as to close aperture 22, made in the top of cover 5, through which aperture the shaft passes, and thus prevents any leakage of mercury when the meter is being shipped. Attached to the shaft is also a weight 23, which further serves to balance the armature.

24 is a gear-wheel, which is connected to

shaft 9, and meshes with a gear-wheel 25 at right-angles to it attached to a shaft 26, which is supported by a U-shaped member 30, which is fastened to member 5. Attached to shaft 26 is a pointer 27, which is used to indicate the readings of the meter, the dial 28 being provided with suitable markings for that purpose. The pointer and dial are visible through glass 3 in front of the meter. Attached to shaft 26 is a balancing weight 31 to compensate for the weight of the pointer 27 in the well understood manner.

29 is a spiral spring, one end of which is attached to the shaft of the meter, and the other end to a support 32 fastened to arm 12, so that when the armature and shaft revolve in a certain direction, they wind up the spring, and a deflection in proportion to the resiliency of the spring is shown by the pointer 27.

In using my meter, I connect one conductor of the circuit, which I desire to measure, so that the current will flow through one of studs 19, connections 18, conductor 17, and through the armature, and will flow out through the other conductor 17, connections 18 and studs 19. Coils 16 of the potential coil are connected across the circuit which it is desired to measure, so that the meter will be a wattmeter, and will have a torque proportional to the product of the current and the voltage. When the connections are made as I have described, and the current is flowing in the circuit, the armature will tend to revolve in a certain direction, and will be opposed by the action of the spring, until a condition of equilibrium is obtained where the torque of the meter armature is equal to the restraining torque of the spring, at which point the armature will remain in a constant position and the amount of energy consumed may be read by the position of needle 27 in front of dial 28.

45 It will be obvious to those skilled in the art that while I have described a meter where the torque on the armature is produced by the interaction of the current flowing through the armature and a magnetic field which varies with the potential and is caused by potential windings upon an iron core in the well understood manner, that I may replace the potential magnets by permanent magnets, and thus obtain an 50 ammeter where the torque on the armature

will be simply proportional to the current flowing in the circuit.

While I have described a certain form in which my invention may be carried out, I do not limit myself to this form, but seek 60 in the appended claims to cover all forms and arrangements which do not depart from the spirit of my invention, and are within the scope of the appended claims.

What I claim as new, and desire to secure 65 by Letters Patent of the United States, is,—

1. The combination in a mercury meter, of a mercury containing receptacle with mercury therein, composed of two substantially disk-shaped members, an armature mounted 70 on a shaft rotatable in the mercury, magnets in operative relation with the armature, a back for the meter, a member attached thereto supporting the operative parts of the meter having two arms supporting the magnets, and an upper arm retaining the upper portion of the shaft, a spring restraining the movement of the shaft, and means indicating the extent of the shaft's movement. 75

2. The combination in a mercury meter, 80 of a mercury containing receptacle with mercury therein, composed of a magnetic and a non-magnetic member each substantially disk-shaped, a disk-shaped armature mounted on a shaft rotatable in the mercury, conductors leading into the mercury for conveying current to the armature, two magnets energized by windings whose current varies with the potential of the circuit to be measured, in operative relation to the armature and disposed on opposite sides of the shaft, a back for the meter, a member attached thereto supporting the working parts of the meter, having two arms for supporting the magnets and a third arm carrying an 85 upper bearing for the shaft, a pointer geared to the shaft for indicating the extent of its movement, a spiral spring fastened to the shaft for restraining its movement, and a weight on the shaft counter-balancing the 90 buoyant effect of the mercury on the armature. 95

In witness whereof, I have hereunto set my hand this eighteenth day of August, 1908.

HARRY N. ATWOOD.
